UNITED STATES PATENT OFFICE.

LLOYD G. COPEMAN, OF FLINT, MICHIGAN.

REFRIGERATING APPARATUS.

Application filed June 9, 1922. Serial No. 566,930.

To all whom it may concern:

Be it known that I, LLOYD G. COPEMAN, citizen of the United States, residing at Flint, in the county of Genesee and State 5 of Michigan, have invented certain new and useful Improvements in Refrigerating Apparatus, of which the following is a specification.

This invention relates to refrigerating 10 apparatus and has for its object a refrigerating apparatus which utilizes the circulation of cold water through the refrigerating box as a cooling medium. This circulation is controlled by a valve in the 15 water line which is regulated by a thermostat, preferably placed in the water line so that when the water in the coils in the box has absorbed all the heat that is possible, a new supply of fresh cold water is drawn in 20 the coils. This much of the construction is old and is described and claimed in my previous Patent 1,472,266, October 30, 1923 and Patent No. 1,409,283, dated March 14, 25 1922.

25 The improvement here to be described and claimed resides in the arrangement whereby a more efficient air circulation is had. In my prior application No. 529,114 I have described and claimed a refrigerating 30 system of a similar character, in which a condensing chamber is located above the food chambers in the box, and the air is caused to drop from the condensing chamber down into one food chamber, thence through an opening in the partition and ascend in the opposite food chamber, and then into the condensing chamber. This arrangement achieves very good 35 results, but even better results are to be had 40 by the improvement which I hereinafter claim and describe.

This improvement consists in a structure so arranged that the cold air will pass down the back of the refrigerating box and 45 ascend along the front of the box adjacent the doors which are the warmest regions in the refrigerator. Preferably the same condensing chamber is employed as is described and claimed in application No. 50 529,114, however, it is possible to do away with this condensing chamber where the coils are exposed in a cold air passageway at the back of the refrigerator which is 55 in the interior of the back wall. This constitutes a very valuable improvement in obtaining better results in circulation, as it

permits the chilling of the air during the entire descent of the air from the top of the box to the bottom. This will be more fully described in the detailed description following:

In the drawings:

Fig. 1 is a vertical cross section of the apparatus taken from side to side.

Fig. 2 is a vertical cross section of the apparatus taken from front to back.

Fig. 3 is a top plan view of the apparatus.

Fig. 4 is a fragmentary section taken on the line 4—4 of Fig. 2.

As described in my previous applications, 70 the water is taken into the box through an intake pipe *a*, ascends to the header *b*, where it is distributed through coils *d* at the sides, coils *e* at the back and coils *f* through the partition. The coils *d* also cross the bottom of the food chamber as is 75 shown in Fig. 1. In the top of the box is the condensing chamber *g* provided with a tray *h* to collect and discharge the moisture that drops from the condensing coils *i*. These condensing coils connect through pipe *j* with the header *b* and discharge through the pipe *k* into the partition coils *f*. These coils all reunite in the lower 80 header *m*. This lower header has two or more discharge pipes—two are here shown—one, pipe *n* connects with the usual service lines in the house or building, the other, pipe *o*, is a waste line in which is a check valve *r* held closed by a spring of sufficient strength to prevent the discharge 85 of water therefrom when service water is being drawn. The discharge from the waste line is also controlled by a valve *q*, operated by a motor *M*. This motor is controlled by a thermostat *t*, which has a barrel *u* inserted in the upper header *b*. I have not described and shown the thermostat, the motor and transmission connection in detail, for the reason that these are 90 fully described and claimed in my other applications and are not part of the present invention except as constituting the environment in which my invention is located.

The present invention resides in the arrangement of the coils and passageways to achieve the best possible air circulation. It will be noticed that the back coils *e* that are laid in the stone work *u* (the stone work is described and claimed in my previous application No. 477,906) are exposed somewhat at the rear and that a cold air passageway *v*

- is located at the rear of the box between the encasing stone work and insulating walls. Preferably, another set of coils *w* leads off from the connecting pipe *k* and is hung in 5 the cold air passageway *v*, as is clearly shown in Figs. 2 and 3. At the bottom of the cold air passageway, slightly above the floor of the food chamber are a pair of openings *x*, these permit the air descending 10 through the cold air duct discharging into the bottom of the food chambers. It then ascends along the front of the food chamber through the ports *y* into the condensing chamber *g*.
- 15 Now, obviously, the water pipes which are not encased in the stone work will chill the air more than the pipes which are encased in the stone work. This results in the condensing pipes in the condensing chamber 20 and exposed pipes in the cold air duct causing the air to chill and descend. On the other hand the warmest region in the refrigerator will be adjacent the front doors which have no coils in their walls. Consequently 25 the air can descend in the cold air duct and rise in the front of the food chamber along the door, creating a complete cycle of circulation through the condenser chamber or top air passage.
- 30 By utilizing a condensing chamber above the food chambers, together with the moisture collecting tray, the moisture in the air collects on the pipes in the condensing chamber and consequently can be taken care of 35 and discharged without getting the food chambers wet; otherwise it would be found that the tops of the food chambers would condense the water and there would be an objectionable dripping therein. Any moisture 40 that collects in the back cold air duct can easily be collected at the bottom of this duct and led away. There would be very little if any moisture when the condensing chamber is used at the top, however, if the 45 condensing coils are eliminated and only the cold air duct coils used in the interest of getting the greatest cubical capacity for the food chamber, then the exposed coils in the rear duct will act as condensing coils and 50 the moisture will be collected in this chamber. I prefer, however, to use the condensing chamber, but it would be possible that fairly good results can be achieved by eliminating the condensing coils and using simply 55 an air passage at the top, or for that matter the air passage could be eliminated and only a port used to connect the top of the cold air duct with the top of the food chamber.
- What I claim is:
- 60 1. In a refrigerating apparatus, the combination of a box provided with a food chamber, and a door, and provided with stone work lining for the food chamber, coils for circulating cold water through said 65 stone work lining, said coils being partially

exposed on the rear side of the lining at the back of the food chamber, a cold air duct located between the rear lining and the wall of the box and arranged to take air from the top of the box and cause same to descend and be discharged in the bottom of the food chamber, the said box being arranged to cause the air to ascend in the warm region at the front of the food chamber adjacent the door. 75

2. In a refrigerating apparatus, the combination of a box provided with a food chamber and a door and a lining for said food chamber, said box provided also with an air passageway from the front of the food chamber across the top of the box above the lining and with a cold air duct leading from said passageway at the rear of the box and to the rear of the lining of the food chamber, and means for circulating 80 cold water through the lining of the refrigerator and around the said cold air duct, said duct discharging into the lower portion of the food chamber at the rear, whereby the chilled air descends in said duct and 85 the warm air ascends adjacent the front of the food chamber and passes through the said top passageway to the said cold air duct. 90

3. In a refrigerating apparatus, the combination of a box provided with a food chamber and a condensing chamber above the food chamber, the said box arranged to provide a cold air duct leading from the condensing chamber along the rear of the 100 food chamber and discharging into the bottom thereof, concealed coils for circulating cold water around the food chamber, exposed coils for circulating cold water in the condensing chamber and exposed coils for 105 circulating cold water in the said cold air flue whereby circulation of the warm air up the front of the food chamber into the port connecting the food chamber and the condensing chamber, thence through the condensing chamber and down the cold air flue, 110 is promoted.

4. In a refrigerating apparatus, the combination of a box provided with a food chamber and door and a stone work lining 115 for the food chamber, coils, for circulating cold water, imbedded in said stone work and partially exposed at the rear of the stone work, the said box being provided with an air passageway across the top above the 120 stone work and a passageway down the back between the stone work and the wall of the box forming a cold air duct that discharges cold air near the bottom of the food chamber thereinto, while the warm air ascends 125 along the doors and discharges into the top passageway at the front and top of the food chamber.

5. In a refrigerating apparatus, the combination of a box provided with food cham- 130

- ber and a door and a lining for the food chamber, said box provided with a passageway leading from the top and front of the food chamber and across the top above the lining and a passageway down the back behind the lining, coils, for circulating cold water, imbedded in said lining and partially exposed in the rear of the lining at the back of the box, the said passageway down the back forming a cold air duct discharging near the bottom of the food chamber thereinto, whereby the warm air will rise adjacent the door of the food chamber and discharge into the top passageway through a port at the top in the front of the food chamber.
6. In a refrigerating apparatus, the combination of a box provided with a food chamber and a door and a lining for the box, the said box also provided with an air passageway leading from the top and front of the food chamber across the top of the box above the lining and a passageway leading down the back of the box behind the lining to form a cold air duct discharging near the bottom of the food chamber thereinto thereby causing warm air to ascend along the door and discharge into the top air passageway and descend through the said cold air duct, means for circulating water through the lining and a separate set of coils for circulating cold water located in the cold air duct for chilling the air descending therefrom.
7. In a refrigerating apparatus, the combination of a box provided with a food chamber and a door, said box also provided with a condensing chamber at the top and a cold air duct leading from said condensing chamber and running down at the rear between the wall of the food chamber and the exterior walls of the box, means for circulating fresh pressure driven water through the walls of the food chamber and through the condensing chamber and along the cold air duct, said cold air duct discharging near the bottom of the food chamber thereinto, thereby causing the warm air to rise along the door and discharge into the condensing chamber at the top and front of the food chamber.
8. In a refrigerating apparatus, the combination of a box provided with a food chamber and a door, said box also provided at the top with a condensing chamber communicating at the front with said food chamber and provided at the back with a cold air duct leading therefrom, a stone work encasement for the food chamber, coils for circulating fresh pressure-driven water through the stone work encasement and circulating water contiguous to the cold air duct to chill the same, said cold air duct discharging near the bottom of the food chamber thereinto, whereby air is caused to descend.
9. In a refrigerating apparatus, the combination of a box provided at the top with a condensing chamber and provided below with a food chamber having a door and a stone work encasement for the food chamber, a cold air duct located behind the stone work for circulating cold air from the condensing chamber down the back of the stone work and discharging same into the back of the food chamber, a port connecting between the top and front of the food chamber and condensing chamber, and means for circulating cold pressure driven water in the walls of the stone work, in the condensing chamber, and contiguous to the cold air duct.

In testimony whereof I affix my signature.

LLOYD G. COPEMAN.
